LETTER ASSEMBLY

Nicholas Barbieri, Providence, R. I., assignor to
 Uncas Manufacturing Company, a corporation
 of Rhode Island

Application October 21, 1941, Serial No. 415,923

5 Claims. (Cl. 18—47.5)

This invention relates to a portable unit assembly of letters or characters such as may be used for jewelry worn on the person such as a brooch, or it may be used in larger sizes for a counter display. The invention, however, in all cases is of a portable character and distinguishable from a permanent mounting or a large interchangeable mounting of letters such as theater marquees and the like.

The retail merchant heretofore in selling names, such as made up in brooches or other articles of jewelry, or in certain portable desk or counter words, has had to send to a manufacturer to make up these words by usually sawing the group of letters from a solid piece of stock. This requires specialized skilled work and is relatively expensive and a business that is of difficult nature to handle.

One of the objects of this invention is to simplify the formation of a group of letters such as the name of an individual, by providing each of the letters formed in such a way that they may be assembled on a common element such as a bar.

Another object of the invention is to form the letters and their mount of a plastic material so that a solvent may be applied to make an integral unit and one in which the letters will not become detached, one from the other.

Another object of the invention is to provide an arrangement which is sufficiently flexible to supply the demand so that a large amount of stock need not be carried on hand.

With these and other objects in view, the invention consists of certain novel features of construction, as will be more fully described, and particularly pointed out in the appended claims.

In the accompanying drawing:

Fig. 1 is a top plan view of a unit formed in accordance with this invention;

Fig. 2 is a rear view of the structure shown in Fig. 1;

Fig. 3 is a rear view with a pin stem, its joint and catch mounted thereon;

Fig. 4 is a top edge view of the structure shown in Fig. 3;

Fig. 5 is a section on line 5—5 of Fig. 1;

Fig. 6 is a section similar to Fig. 5 with the bar omitted;

Fig. 7 is a perspective view of one of the letters; and

Fig. 8 is a perspective view of this letter assembled with the fragmental portion of a bar.

In proceeding with this invention, I mold

from some plastic material, such as Celluloid, a plurality of letters, each provided with a groove in its rear surface and I form a bar which will fit into this groove of the same material and then soften it sufficiently so that the surfaces of the bar and the walls of the groove weld together, or I may cement the surfaces together to form a single unit structure. The bars are formed in any length and cut off at the termination of the group of letters which are provided. The mounting means is assembled with the group of letters thus formed, and may consist of a pin stem joint and catch for the formation of a brooch while other mounting means may be provided for other uses as will of course be apparent.

With reference to the drawing, 10 designates one of the letters, and by the term "letters" I mean either letters of the alphabet, numbers or any characters. Each letter is formed by molding in the outline shape desired, and will have a front face 11 and a back face 12, there being a groove 13 in the back face having side walls 15 and 16 inclined away from each other as they proceed from the back face 12 inwardly, thus forming a dovetail slot when viewed in cross section, as shown in Figs. 5 and 6.

A bar such as designated 17 (see Fig. 8) is provided of an extended length and will also have its top and bottom surfaces 18 tapered so as to fit the groove 13 by reason of its edges 19 engaging the edges 15. Such shaping makes it desirable for each of the letters to be slid onto the bar, although the undercutting is so small that in some instances there will be sufficient resilience of the letters to permit of them being removed from the bar by springing of the stock sufficient to be lifted therefrom. The depth of the groove 13 and the thickness of the bar 17 is such that when the bar is inserted in the groove as illustrated in Figs. 5 and 8, the rear surface of the bar 19 will be flush with the rear surface 12 of the letters.

If it is desired to assemble the word "Jenny," such, for instance, as on an individual order, I will put the letters j e n n y onto the bar 17 and then cut the bar at the end 20 to be flush with the edge 21 of the letter j and I will cut the end of the bar 22 on an incline so as to be flush with the edge 23 of the letter y. After this assembly has been formed any suitable mounting may be made for supporting the grouping thus formed.

In order to make a permanent assembly of the 55 Celluloid bar and the Celluloid letters, I may dip

the entire unit in a solvent for the Celluloid material or other plastic if used, and by reason of the solvent the edges of the bar will weld to the edges of the groove in which it is inserted so that the assembly becomes a permanent unit.

To make a brooch from the assembly I will attach the pin stem joint 24 with its pin stem 25 and a pin stem catch 26 on the back of the bar. Various lengths of pin stems may be provided in accordance with the length of the group of 10 letters utilized.

In some cases I may utilize a colored plastic for the letters 10 and a different colored bar or a transparent bar 11. It will of course be apparent that by reason of the individual parts going to make up the assembly that the color scheme may be varied for each of the letters or for some of the letters and the bar so that different contrasts may be provided.

I claim:

1. The method of making to order a portable unit assembly of letters which consists in the step of pre-making a plurality of plastic letters with a groove in the back thereof, forming a plastic bar of extended length to fit in said groove, assembling on order the selected group of letters on said bar and cutting the bar on completion of the assembly to the length necessary for mounting said group and then dipping the assembly in a solvent to apply said solvent to the joint between the letters and the bar to weld the same together into an integral unit.

2. The method of making to order a portable unit assembly of letters which consists in the step of pre-making a plurality of plastic letters with a groove in the back thereof, forming a plastic bar of extended length to fit in said groove, assembling on order the selected group of letters on said bar and cutting the bar to the length necessary for mounting said group, and then applying a solvent to the joint between the letters

and the bar to weld the same together into an integral unit.

3. The method of making to order a portable unit assembly of letters which consists in the step of pre-making a plurality of plastic letters with a groove in the back thereof, forming a plastic bar of extended length to fit in said groove, assembling on order the selected group of letters on said bar and cutting the bar on the completion of said assembly to the length necessary for mounting said group, and along the line of the terminal letters, and then applying a solvent to the joint between the letters and the bar to weld the same together into an integral unit.

4. The method of making to order a portable unit assembly of letters which consists in the step of pre-making a plurality of plastic letters with a groove in the back thereof, forming a plastic bar of extended length to fit in said groove, assembling on order the selected group of letters on said bar and cutting the bar to the length necessary for mounting said group, and then applying a solvent to the joint between the letters and the bar to weld the same together into an integral unit and applying a mounting to the back of said bar.

5. The method of making to order a portable unit assembly of letters which consists in the step of pre-making a plurality of plastic letters with a groove in the back thereof, forming a plastic bar of extended length to fit in said groove, assembling on order the selected group of letters on said bar and cutting the bar to the length necessary for mounting said group, and then applying a solvent to the joint between the letters and the bar to weld the same together into an integral unit and applying a pin stem joint and catch to the back of said bar.
